Primary Examiner — Michelle E Wilson*Assistant Examiner* — Sanjeev Paul(74) *Attorney, Agent, or Firm* — Polsinelli PC(57) **CLAIM**

I claim the ornamental design for a visor, as shown and described.

DESCRIPTION

FIG. 1 is a front perspective view of a first embodiment of a visor, showing my new design;

FIG. 2 is a front elevational view thereof;

FIG. 3 is a top plan view thereof;

FIG. 4 is a bottom plan view thereof;

FIG. 5 is a left side elevational view thereof, the right side view being a mirror image; and,

FIG. 6 is a rear perspective view thereof.

1 Claim, 6 Drawing Sheets(56)
